SIDNEY D. KLAUS

BY

Marie S. Spindleton

ATTORNEY

UNITED STATES PATENT OFFICE.

SIDNEY D. KLAUS, OF NEW YORK, N. Y.

FILM DRYING AND DEVELOPING APPARATUS.

Application filed May 28, 1921. Serial No. 473,251.

To all whom it may concern:

Be it known that SIDNEY D. KLAUS, citizen of the United States, and resident of the city of New York, in the county and

State of New York, has invented certain new and useful Improvements in Film Drying and Developing Apparatus, of which the following is a specification.

This invention relates to film drying and developing apparatus.

More particularly, the invention is directed to a device adapted for use in developing and drying dental X-ray films.

One object thereof is the provision of a device of the character described which shall be adapted for easy and handy use with the usual dental lathe equipment of the dentist's office.

Another object is to provide a device of the type described which may be adapted for use in first developing and then rapidly drying a plurality of dental films.

A further object is to provide in a device of the character described a film holder in which a dental film may be securely held while being developed and while being dried without an appreciable portion of the film coming in contact with the holding members.

A still further object is to provide a device of the character described which shall be efficient in its operation and simple in construction and use to a high degree.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings, in which is shown one of various possible illustrative embodiments of this invention,

Fig. 1 is a vertical cross sectional view showing an embodiment of this invention in use when developing the dental film;

Fig. 2 is a partial vertical elevational view showing the embodiment of the invention shown in Fig. 1 mounted on the dental lathe and in use in drying the film; and

Fig. 3 is a cross-sectional view cut along

line 3—3 of Fig. 1 showing in bottom plan 55 the head member in which the film holders are held.

Referring in detail to the drawing, the embodiment of the invention there shown is seen to comprise a holding member or head 10 in which are removably held the film holders 11 in the manner hereinafter more fully described. This head 10 comprises a preferably cylindrical hub piece 12 hollowed out so as to provide a central screw projection 13 upstanding from the interior bottom support of said hub and on which may thread a cap member 15. The hub 12 is further formed on the interior thereof with an inwardly extending shoulder 15' and depressed from the interior bottom surface of the hub is a concentric arcuately curved recess 25. The cap member 15 is formed with an annular flange 16 of a diameter substantially equal to the internal diameter of the member 12. This cover member is formed with a knurled thumb piece 18 for manipulation thereof and has further an extension 19 interiorly threaded as at 20 for the screw projection 13 of the member 12. When the cover 15 is threaded on to the screw projection 13 in the manner described, the flange 16 rests on the annular shoulder 15' as will be readily understood. Spaced slots 21 are 85 formed in the member 12 and these extend vertically across the outer cylindrical surface of the member 12 and radially on the interior thereof as shown in Fig. 3, intersecting the ridge 25 in indentations 26. 90

The film holder comprises the body portion 22 and a handle portion 23. The body portion 22 is provided with retaining members 24 in the form of portions overturned from the material of the body about the edges thereof, as shown clearly in Fig. 1. These overturned portions upstand from the body portion at a small angularity sufficient for them to abut against the edge of the dental film when the film is in place. As is well known, dental films are made of a somewhat elastic material and the film (shown at 27) may be made to snap in between these retaining members 24 by virtue of its elasticity and in so doing the bounding edges of the film abut against the retaining members 24. When the hub is revolved with the film holder and film 27 in place therein, the

lower edge of the film is thrown centrifugally against the edge 24^a of the bottom retaining member 24 and thus more securely held in place. It will be noted that the securing of the film holder of the type just described is by the restoring force of the elasticity of the film acting against the retaining members 24 and the latter do not cover the film or any portion thereof but simply act against its edges, thus leaving the entire surface of the film fully exposed either for drying or for developing.

The handle portion 23 of the holders 11 is formed with a raised portion 23' corresponding to the indentations 26 so that when a holder 11 is placed in position in the head member by inserting the handle portion 23 into the slot 21, this raised portion 23' fits into the indentation 26 which acts as a socket or journal.

In the use of the device, any desired number of film holders are placed in this way in the slots 21, and the cap member is screwed into place, the flange 17 pressing against the handle 23 to hold the film holder in a given position. When the cover member 15 is given a partial turn in the direction to unthread it from the screw projection 13, the holders are free to rotate in a vertical plane in the indentations 26, and they may be held firmly in a desired position by screwing the cap tightly on the head member. The hub 12 has a tapered central opening 28 and the cap member 13 is likewise tapered as at 29, so as to fit into said opening 28.

When the device is in use for developing a number of dental films, the holders are positioned within the slots and rotated into a downward vertical position as shown in Fig. 1, and then held securely in this position by tightening the cap member 14 as already explained. The tapered pin 30 is fitted into the openings 28, 29, to serve as a support for the head together with the film holders. This pin carries a collar 31 adapted to rest against the cover 32 of the developing vat or vessel 33 containing the developer 34.

After the films are completely developed, they are removed from the vat and the cover member given a partial turn so as to loosen it somewhat, and the holders 11 are turned through an angle of 90° into the position shown in Fig. 2. The pin 30 is then removed and the device slipped on to the tapered shaft 36 of the dental lathe (not shown in full in Fig. 2). When the lathe is set into operation, the drying of the film proceeds by the throwing off of the excess water through centrifugal force, and further by the circulation of and contact with the air.

An added advantage of the type of film holder hereinabove described and of the use thereof in connection with the head member is that the keeping of records of the dental

films is considerably facilitated. Thus the holders 11 may bear numbers such as 1, 2, 3, etc. and a given dental film placed in a holder may be identified by a corresponding number in the dentist's records.

It will thus be seen that there is provided apparatus in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. In a device of the character described, a hub member having recesses formed therein adapted to receive film holders, and means movable on said hub member adapted to act on said film holders when positioned therein to hold them securely in position.

2. In a device of the character described, a hub member having slots formed therein adapted to receive film holders, an exteriorly threaded projection extending centrally from said hub member and a cap having a projection interiorly threaded over said first mentioned projection.

3. A device for holding one or more film holders in various positions comprising a hub member having an annular shoulder on the interior thereof, radial slots cut in said hub member and a cap member provided with an annular flange adapted to rest on said shoulder.

4. In a device of the character described, a hub member having slots formed therein adapted to receive film holders, an exteriorly threaded projection extending centrally from said hub member and a cap having a projection interiorly threaded for said first mentioned projection, said slots being formed with curved indentations as and for the purpose described and specified.

5. In a device of the character described, a film holder having a body portion provided with side and bottom overturned retaining members and a flat handle portion extending from said body portion, said overturned retaining members upstanding from said body portion at a slight angularity.

6. A combined developing and drying apparatus for photographic films comprising a holding device having means whereby the films may be positioned therein and securely held in various positions, said holding device having an opening therein adapted for mounting the same on a shaft.

7. A combined developing and drying apparatus for photographic films comprising

a head member having recesses therein adapted to receive the film holders, a cap for said head member adapted to frictionally engage said holders when said cap is in position on said hub, means in said hub permitting said holders when positioned therein to be rotated at various angles, said hub member and cap

member having central openings therein adapted to be in registry with each other as and for the purpose described and specified. 10

Signed at New York city, in the county of New York and State of New York, this 19 day of May 1921.

SIDNEY D. KLAUS, D. D. S.
